DRAFT DEVICE

William W. Sloane, Chicago, Ill., assignor to
 Goodman Manufacturing Company, Chicago,
 Ill., a corporation of Illinois

Application April 19, 1939, Serial No. 268,678

11 Claims. (Cl. 104—235)

This invention relates to improvements in draft devices, and more particularly relates to improvements in such devices adapted to propel a remotely controlled car or like device in mines underground.

It has heretofore been the practice to use relatively large conveyer cars for hauling coal in mines underground. These cars are usually loaded at the face by hand or by a mobile loader and are moved to the entry or unloading station by power, under remote control. Flexible cables and power driven winding drums have been found to be the most practical means for hauling such cars underground, but difficulty has been encountered in controlling the speed of the car along an undulating roadway. The principal reasons are that since a man cannot be at the car to brake its speed, it tends to travel down grade at a greater rate of speed than the winding speed of the propelling winding drum. This causes slack to form on the draft cable, and frequently causes this cable to foul and be run over and severed by the wheels of the car.

The principal objects of my invention are to remedy this difficulty by providing a simple and novel form of flexible draft means to propel and control the speed of a remotely controlled car, which includes flexible draft and trailing cables and a means controlled by tension on one cable to hold the other cable under tension, to hold the car back while going down grade and thus prevent the formation of slack on the draft cable.

More specifically, the objects of my invention are to provide a novel and improved form of draft means for a remotely controlled car, including two winding drums, each of which has a flexible draft cable wound thereon, and including a means to prevent the formation of slack on the pulling or draft cable, when the car is going down grade, which is so arranged that tension on the draft cable will release a holding means from the unwinding drum an amount sufficient to permit paying off its associated cable, but prevent the free rotation of said unwinding drum, and the release of tension on the draft cable will cause an increase in tension on the trailing cable, which will slow the car down to such an extent that the draft cable is under tension regardless of whether the car is traveling along the level or down grade.

Other objects of my invention will appear from time to time as the accompanying specification proceeds.

My invention may be more clearly understood

with reference to the accompanying drawings wherein:

Figure 1 is a plan view of a car having a draft device constructed in accordance with my invention associated therewith;

Figure 2 is a fragmentary view in side elevation of the device shown in Figure 1, drawn to an enlarged scale;

Figure 3 is an enlarged fragmentary plan view of a portion of the car shown in Figure 1, with parts of the draft device broken away and other parts shown in horizontal section, in order to more clearly illustrate certain details of my invention;

Figure 4 is a view somewhat similar to Figure 2, with the parts positioned differently than in Figure 2 and drawn to an enlarged scale, and showing certain parts broken away and certain other parts in longitudinal section;

Figure 5 is a transverse sectional view taken substantially along line 5—5 of Figure 4; and

Figure 6 is a transverse sectional view taken substantially along line 6—6 of Figure 4.

In the drawings, the embodiment of my invention illustrated is shown as including a pair of winding drums 10, 10, herein shown as being mounted on a car 11, and having flexible cables 12, 12 wound thereon and adapted to be attached at their ends to fixed abutments, for propelling said car. Said car, as herein shown, is of the conveyor type, mounted on track wheels 15, 15 and having a chain flight conveyer 17 extending along the bottom thereof. Said car is somewhat similar to that illustrated in Patent No. 2,143,522, which issued to T. F. McCarthy on January 10, 1939, so will only be described in so far as is necessary to make my present invention clearly understandable.

The winding drums 10, 10 are mounted on the car 11 on parallel spaced transverse shafts 18, 18. Said shafts are mounted at one of their ends on an upright frame member 19 extending along one side of the conveyor, and at their opposite ends on a parallel laterally spaced upright frame member 20 (see Figure 6).

A transverse shaft 21, disposed parallel to and intermediate the shafts 18, 18, is provided to drive either of said winding drums. Said shaft is driven from a motor 24, mounted on the conveyor frame, through a speed reducer 25 and a chain and sprocket drive 26 (see Figures 1 and 2). A pair of spaced apart spur gears 23, 23 are freely mounted on said shaft and are selectively connected therewith by means of a clutch 33. One of said spur gears is disposed adjacent the

frame member 19 and meshes with and drives an annular gear 31, secured to the inside flange of one winding drum 10. The other of said spur gears is disposed adjacent the frame member 20, and meshes with another annular gear 31, secured to the outside flange of the other winding drum 10.

The clutch 33, as herein shown, includes an externally splined member 34 keyed on said shaft between the spur gears 23, 23, and having an internally splined clutch member 35 mounted thereon for slidable movement therealong. Said clutch member is shifted along the member 34 by a suitable arrangement of links and levers so that the internal splines of said clutch member may selectively engage splined hubs 36, 36 of either of the spur gears 23, 23 (see Figure 3).

Referring now in particular to the novel form of holding device for holding the winding drums 10, 10 from rotation in an unwinding direction, and the arrangement whereby tension of the draft cable serves to release the braking means on the unwinding drum a predetermined amount, to permit the trailing cable to be paid off of said unwinding drum under tension and to hold the draft cable under tension at all times, a brake drum 39 adapted to be engaged by a brake band 40, is journaled on each transverse shaft 18, adjacent the inside of the frame member 20. One of said brake drums has an inwardly extending flanged portion 41 which extends within a flanged portion 42 of one winding drum 10 (see Figure 6). The other brake drum has a similar flanged portion which extends within the annular gear 31 of the other winding drum. Since the construction and arrangement of the braking means and the means under control of cable tension on the winding drum for releasing the braking means from or permitting said braking means to be applied to the trailing drum, is similar for both drums, the same part numbers will be applied to the braking and releasing mechanism for each drum and said mechanism for one drum only will herein be described in detail.

The flanged portion 41 of the brake drum 39 has a ratchet 43, which is herein shown as being formed integral therewith, and which is adapted to be engaged by either one of a pair of oppositely disposed spring pressed pawls 44, 44, mounted on the inner periphery of the flanged portion 42 on pivotal pins 45, 45. Said pins are each secured at their ends to a bracket member 46. Said bracket members extend inwardly from opposite sides of the flange 42. Said pawl and ratchet thus permit rotation of the winding drum 10 in a winding direction when the brake drum 39 is held from rotation, but prevent rotation thereof in an unwinding direction.

The friction band 40 is engaged with or disengaged from the brake drum 39 by means of an operating lever 50, having pivotal connection with a lug 51 projecting from one end of said friction band. Said operating lever is pivotally mounted on the frame member 20 on a transverse pivotal pin 53. A lever arm 54 of said operating lever extends outwardly from the pivotal axis thereof and has a rod 55 pivotally connected to the free end thereof. Said rod extends in a direction away from the two drums 10, 10 and is slidably guided in a bracket member 56. A preloaded compression spring 59 is herein shown as encircling the end of said rod opposite from the lever arm 54 and is interposed between the bracket 56 and an abutment member 58 on the end of said rod.

The opposite end of the friction band 40 is held from movement by means of a bell crank 61, which has one of its lever arms pivotally connected to a lug 60 extending from said friction band. Said bell crank is pivotally mounted on the frame member 20 on a pivotal pin 64. A threaded eye bolt 65 is pivotally connected to the other lever arm of said bell crank. Said eye bolt extends through a stop 67 and has a pair of nuts 69, 69 threaded thereon and abutting opposite sides of said stop, to hold said rod and bell crank from movement, and to form a means for adjusting said friction band on its associated brake drum. An abutment member 70 is threaded on the end of said rod and held in fixed relation with respect thereto by means of a nut 71. Said abutment member is adapted to engage the lever arm 54 of the operating lever 50, opposite from the drum to which said abutment has connection, and form an adjustable stop to limit movement of the operating lever 50 and thus limit the extent to which the friction band 40 can be disengaged from its respective brake drum. The spring 59 thus serves to hold the friction band 40 in engagement with the brake drum 39 to hold said brake drum from rotation, and hold the associated winding drum from rotation in an unwinding direction.

Referring now to the novel arrangement whereby tension on one cable 12, as it is being wound on its associated winding drum 10, will release the friction band 40 from the brake drum 39 for the other winding drum 10, to permit rotation of said winding drum in a direction to pay off cable therefrom against a predetermined frictional resistance, but release of tension on said cable as it is being wound on its associated drum will cause said friction band to be applied to the trailing winding drum and retard the speed 40 of the car to such an extent as to keep the draft cable under tension, a bell crank member 73 is mounted on the transverse shaft 18. One lever arm 74 of said bell crank member extends angularly away from said shaft in the direction cable 45 is to be payed from said drum, which is towards the front of the car from one drum and towards the rear of the car from the other drum. Said lever arm is of a U-shaped formation in plan, extending around the winding drum 10 and having its free end also journaled on the shaft 18 (see Figures 1 and 3). A roller 75 is rotatably mounted adjacent the closed end of said arm between the sides thereof. Another lever arm 76 of said bell crank extends in a direction, which in Figure 4 is shown as being in an upward direction for the forward or right hand bell crank, and in a downward direction for the rear or left hand bell crank. A link 77 is provided to connect said last mentioned lever arm with the lever arm 54 of the operating lever 50, associated with the friction band controlling the winding drum 10, opposite from the winding drum with which said bell crank is associated.

The cable 12 is trained from its associated winding drum 10 around the roller 75 in a direction away from said roller, which on the right hand drum in Figure 4 is a downward and forward direction, and on the left hand drum in the same figure is an upward and rearward direction, and then around a roller 79, and away from said roller to a point remote from the car, at which point the end of said cable may be secured. Thus, when one winding drum is rotating in a winding direction, and its cable is attached to a fixed abutment at its free end, to

pull the car towards said abutment, tension of said cable will pivot the bell crank 73 in a clockwise direction. This will move the operating lever 50 against the spring 59 through the link 77, and move the friction band 40 in a direction to release it from its associated brake drum 39 a predetermined amount, to permit rotation of said winding drum in an unwinding direction. When the car tends to coast down grade, the driving cable will tend to slacken, which will permit the spring 59 to apply the friction band 40 to the brake drum 39, which controls rotation of the unwinding drum. This will cause the trailing cable to retard the car, and equalize the speed of the car with that of the winding drum.

In order to prevent free rotation of either winding drum 10, when it is paying off cable, the abutment member 70 is provided to limit movement of the lever arm 54. The amount that the friction band 40 is released from its associated brake drum may thus be regulated by adjusting the position of said abutment member on the threaded rod 65, to permit release of said friction band from its associated brake drum an amount sufficient to permit rotation of said winding drum under a predetermined frictional resistance.

It may accordingly be seen that a novel form of draft and control means for a remotely controlled car has been provided, which is controlled by tension on the draft cable so that as cable is wound on one drum and the tension thereof reaches a predetermined value, this cable will release a holding means from the opposite drum an amount sufficient to permit cable to be payed therefrom under the control of friction, and thus hold the draft and paying off cables under tension at all times, and prevent slack from forming in the draft cable and minimize the tendency for said draft cable to foul or be run over by the car wheels, when the car is traveling down grade.

While I have herein shown and described one form in which my invention may be embodied, it will be understood that the construction thereof and the arrangement of the various parts may be altered without departing from the spirit and scope thereof. Furthermore, I do not wish to be construed as limiting myself to the specific embodiment illustrated, excepting as it may be limited in the appended claims.

I claim as my invention:

1. In a draft device, a frame, two winding drums mounted on said frame, a flexible cable adapted to be wound on each of said drums, means for selectively driving either of said drums, one of said drums being adapted to serve as a propelling drum and the other of said drums being adapted to serve as a retarding drum, separate friction means associated with each of said drums, for retarding rotation thereof in an unwinding direction, and means mounted on said frame and engaged by the propelling cable and having operative connection with the retarding means for the retarding drum and actuated by tension on said cable, for positively releasing the retarding means from the retarding drum and permitting said retarding means to be applied to said retarding drum upon the release of tension from said propelling cable.

2. In a draft device, a frame, two winding drums mounted on said frame, each of said winding drums being adapted to have a flexible cable wound thereon, and each being adapted to serve alternately as a draft device and a re-

tarding device, separate holding means for each drum, for holding each drum from rotation in an unwinding direction, and means engaged by the draft cable and actuated by tension thereof, for releasing said holding means from the retarding drum a predetermined amount, or permitting said holding means to be applied thereto upon release of tension in said draft cable, to maintain both cables under tension, including 10 a pair of pivoted members, one of said pivoted members being associated with one drum and the other being associated with the other drum, a connection from each of said pivoted members to the holding means for the drum opposite from 15 the drum with which said pivoted member is associated, and an operative connection between said flexible cables and said associated pivoted members.

3. In a draft device, a frame, two winding drums mounted on said frame, each of said winding drums being adapted to have a flexible cable wound thereon, and each being adapted to serve alternately as a draft device and a retarding device, separate holding means for each drum, for holding each drum from rotation in an unwinding direction, and means engaged by the draft cable and actuated by tension thereof, for releasing said holding means from the retarding drum or permitting said holding means to be applied thereto upon release of tension on said draft cable including a pair of bell cranks, one of said bell cranks being associated with one drum and the other being associated with the other drum, an operative connection 20 from one arm of each of said bell cranks to said holding means for the drum opposite from the drum with which said bell crank is associated, and a connection from said flexible members to the other arms of said bell cranks, for 25 pivotally moving said bell cranks in a direction to release said holding means from the unwinding drum, upon a predetermined tension in said 30 associated cable when the associated cable engaging said arm is being wound in and is acting 35 as a draft device.

4. In a draft device for a car or like apparatus, a frame, two winding drums mounted on said frame, a flexible cable adapted to be wound on or payed off of each of said winding drums, means for selectively driving either of said winding drums, one of said drums and cables being adapted to serve as a draft device and the other of said drums and cables being adapted to serve as a retarding device, separate braking means 50 for each of said winding drums for holding said winding drums from rotation in an unwinding direction, and means mounted on said frame and engaged by the draft cable and actuated by tension thereof, for releasing said braking means from the retarding drum or permitting said braking means to be applied thereto upon the release of tension in said draft cable, to maintain both cables under tension and to prevent the formation of slack in the draft cable when 55 the car is traveling down grade.

5. In a draft device, two flexible cables, a frame, two winding drums mounted on said frame, each of said winding drums being adapted to wind in or pay off one of said cables, means for selectively driving either one of said winding drums in a winding direction, separate braking means for each of said winding drums for holding said winding drums from rotation in an unwinding direction, yieldable means for applying said braking means, and means mounted on said 60

frame and actuated by tension of the cable on the drum which serves as the winding drum and acting against said yieldable means which applies the braking means to the drum which serves as the unwinding drum, for releasing said braking means from said unwinding drum or permitting said braking means to be applied thereto to prevent the formation of slack on either the take-up or paying-off cable, including a separate pivoted member associated with each drum, a connection from one of said cables to one of said pivoted members, an operative connection from said pivoted member to said braking means on said other drum, for releasing said braking means, and an adjustable stop for limiting the amount of release of said braking means from said drum.

6. In a vehicle propelling device, a car, two winding drums mounted on said car, each being adapted to serve alternately as a draft drum and a retarding drum, for reversely propelling the car, a flexible cable on each winding drum and adapted to be wound on or payed off therefrom, said cables being adapted to extend in opposite directions from said car and have their free ends attached to fixed abutments remote from said car, means for selectively driving said drums, braking means for each drum, for holding each drum from rotation in an unwinding direction, and means mounted on said car and actuated by tension of the draft cable for releasing said braking means from said retarding drum an amount sufficient to permit rotation of said drum in an unwinding direction, but to provide sufficient drag on said drum to prevent the formation of slack in the retarding cable, and permitting said braking means to be applied to said retarding drum upon the slackening of tension of said draft cable, to permit the retarding drum to hold the car when traveling down grade, including a pair of pivoted members, one of said pivoted members being associated with the draft drum and engaged by the cable of that drum and having operative connection with the braking means of the retarding drum and the other of said pivoted members being associated with the retarding drum and engaged by the cable of that drum and having operative connection with the braking means of the draft drum to permit reverse operation of said drums.

7. In a vehicle propelling device, a car, two winding drums mounted on said car, each being adapted to serve alternately as a draft drum and a retarding drum, for reversely propelling the car, a flexible cable on each winding drum and adapted to be wound on or payed off therefrom, said cables being adapted to extend in opposite directions from said car and have their free ends attached to fixed abutments remote from said car, means for selectively driving said drums, braking means for each drum for holding each drum from rotation in an unwinding direction, and means mounted on said car and actuated by tension of the draft cable for releasing said braking means from said retarding drum an amount sufficient to permit rotation of said drum in an unwinding direction, but to provide sufficient drag on said drum to prevent the formation of slack in the retarding cable, and permitting said braking means to be applied to said retarding drum upon the slackening of tension of said draft cable, to permit the retarding drum to hold the car when traveling down grade, including two bell crank members, one of said bell crank members being associated with the draft drum

and having a lever arm engaged by the cable of that drum and having another lever arm having operative connection with the braking means for the retarding drum, and the other of said bell

5 crank members being associated with the retarding drum and having a lever arm engaged by the cable of that drum and having operative connection with the braking means of the draft drum, to permit reverse operation of said drums.

10 8. In a vehicle propelling device, a frame, two winding drums mounted on said frame, each of said winding drums being adapted to have a flexible cable wound thereon, said cables extending in opposite directions from their respective drums and adapted to have their free ends attached to fixed abutments remote from said winding drums, means for selectively driving either of said winding drums in a winding direction, separate braking means for each of said winding drums, for holding said winding drums from rotation in an unwinding direction, yieldable means mounted on said frame for applying said braking means, and means engaged by the cable on the winding drum and actuated by tension thereof and acting against said yieldable means which applies the braking means on the unwinding drum, for releasing said braking means from the unwinding drum an amount sufficient to permit said drum to pay off its associated cable, 20 but to provide a predetermined drag on said drum, to prevent the formation of slack in said cable as it is being unwound therefrom, and permitting said braking means to be applied to said unwinding drum upon the slackening of tension of said draft cable, whereby said unwinding drum may serve to maintain the draft cable under tension.

9. In a vehicle propelling device, a frame, two winding drums mounted on said frame, each of said winding drums being adapted to have a flexible cable wound thereon, said cables extending in opposite directions from their respective drums and adapted to have their free ends attached to fixed abutments remote from said winding drums, means for selectively driving either of said winding drums in a winding direction, separate braking means for each of said winding drums, for holding said winding drums from rotation in an unwinding direction, yieldable means mounted on said frame for applying said braking means, and means engaged by the cable on the winding drum and actuated by tension thereof and acting against said yieldable means which applies the braking means on the unwinding drum for releasing said braking means from the unwinding drum an amount sufficient to permit said drum to pay off its associated cable, but to provide a predetermined drag on said drum, to prevent the formation of slack in said cable as it is being unwound therefrom and permitting said braking means to be applied to said unwinding drum upon the slackening of tension of said draft cable, whereby said unwinding drum may serve to maintain the draft cable under tension, said means for releasing said braking means including a separate pivoted member associated with each drum, an operative connection from one cable to said associated pivoted member, and a connection from said pivoted member to said braking means on said other drum.

60 10. In a vehicle propelling device, a frame, two winding drums mounted on said frame, each of said winding drums being adapted to have a flexible cable wound thereon, said cables extending in opposite directions from their respective drums and adapted to have their free ends attached to

fixed abutments remote from said winding drums, means for selectively driving either of said winding drums in a winding direction, separate braking means for each of said winding drums, for holding said winding drums from rotation in an unwinding direction, yieldable means mounted on said frame for applying said braking means, and means actuated by tension of the cable on the winding drum and acting against said yieldable means which applies the braking means on the unwinding drum, for releasing said braking means from the unwinding drum an amount sufficient to permit said drum to pay off its associated cable, but to provide a predetermined drag on said drum, to prevent the formation of slack in said cable as it is being unwound therefrom and permitting said braking means to be applied to said unwinding drum upon the slackening of tension of said winding cable, whereby said unwinding drum may serve to maintain the draft cable under tension, said means for releasing said braking means including a separate bell crank associated with each drum, a connection from one of said cables to one arm of said bell crank, and

a connection from the other arm of said bell crank to said braking means of said other drum.

11. In a vehicle propelling device, a car, two winding drums mounted on said car, each of said winding drums being adapted to have a flexible cable wound thereon, said cables being adapted to extend in opposite directions from said car and to be attached to fixed abutments remote from said car, one of said drums and cables being adapted to propel said car and said other drum and cable being adapted to retard said car and prevent it from over-running the propelling cable, separate retarding means associated with each of said drums, for retarding rotation of said drums in an unwinding direction, and means mounted on said car and engaged by the cable on the propelling drum and actuated by tension thereof, for releasing said retarding means from the retarding drum and permitting said retarding means to be applied to said retarding drum upon the release of tension on said propelling cable.

WILLIAM W. SLOANE.
